METHOD OF MAKING SLIP-LASTED SHOES
HAVING METATARSAL PADS

Charles Longini, Cincinnati, Ohio

Application December 3, 1949, Serial No. 130,917

2 Claims. (Cl. 12—142)

1

This invention is directed to shoes of the type having built-in cushions or pads adapted to provide corrective support to weakened or infirm portions of the foot and is particularly directed to shoes of this type manufactured by the slip lasting process.

Certain types of corrective shoes employ resilient pads or cushions which are strategically located to distribute the moving load of the wearer's weight and to support the arch or ball of the wearer's foot. It is highly desirable to anchor these supporting pads or so-called buttons by building them directly into the shoe and thus prevent them from shifting from proper supporting relationship or becoming detached and lost. Moreover, it is preferred to conceal the pads directly beneath the sock lining so that they bulge the lining inwardly in proper supporting relationship to the foot. However, it is very difficult to build shoes of this type on standard lasts, since the presence of the buttons presents difficult alignment and assembly problems, and often requires special manufacturing techniques involving expensive processing steps. The problems are particularly acute in the case of slip-lasted shoes, where the upper and sock lining are firmly attached together prior to the lasting operation and the outsole, heel and platform assembly is fastened directly to the sock lining during lasting. It has heretofore been prohibitively awkward and expensive to manufacture correctly shaped slip lasted shoes including built-in buttons concealed by the sock lining because there is no room between the sock lining and platform to accommodate the buttons.

The primary objective of this invention is to provide a method for making shoes containing built-in corrective pads, such as metatarsal and arch buttons, in which provision is made for the accommodation and location of the pads without necessitating the alteration of standard shoe parts or their relative relationship to each other. In accordance with this invention, accommodation for the pads is built directly into the shoe either prior to, or during the lasting process without interfering with the normal assembly, shaping and lasting operations. In fact, the pads themselves are not added until after the shoe is otherwise completed and consequently their presence does not complicate the building operation. After the shoe has been removed from the last, the buttons are inserted and fastened in place without necessitating interference with the stitches or cement holding previously assembled shoe parts together. Thus, correctly shaped and pro-

2

portioned shoes manufactured on standard lasts by the slip lasting process can be provided with built-in corrective buttons.

More specifically, the process of this invention 5 contemplates the provision of an envelope formed between the sock lining or insole and a specially provided flap which I choose to call the shank lining. Prior to the lasting operation, the shank lining and sock lining are overlaid by the assembler so that the shank lining overlies the sock lining in face to face relationship. A partially sealed envelope is then formed preferably by stitching common edges of the sock lining and shank lining together. However, one edge of the 15 shank lining is left free thereby forming an envelope mouth adapted to subsequently receive the metatarsal and arch supporting buttons. In the slip lasting process the seam between the shank lining and sock lining may be formed at the same time that the upper is joined to the sock lining, and it will then be integrated into the seam between the upper and sock lining. This 20 assembly is then slip-lasted and the outsole, heel and, if desired, a platform are attached. During 25 the lasting operation, the envelope is empty and the thin shank lining resides flatly against the sock lining and the upper conforming snugly to the last. Consequently, it does not interfere with the proper shaping or assembly of the shoe.

After the shoe is removed from the last, the 30 mouth of the envelope is opened by turning back the free edge of the flap and the metatarsal and arch supporting buttons are slipped into proper location within the envelope. These buttons may then be firmly fastened into position to either the 35 sock lining and the upper or the underside of the shank lining. The shank lining flap is then returned to proper position over the sock lining, and the upper and the mouth of the envelope 40 sealed by securely fastening the free edge of the shank lining to the sock lining.

Other advantages and objections of this invention will be apparent from the following description of the drawings in which:

Figure 1 is a perspective view of an upper, 45 shank lining, sock lining, and platform wrapper adapted to be used in the process of this invention.

Figure 2 is a side view of the pre-lasting assembly of the parts shown in Figure 1.

Figure 3 is a cross sectional view taken along line 3—3 of Figure 2.

Figure 4 is a side view of a lasted shoe constructed in accordance with this invention.

Figure 5 is a top view of the shoe after lasting.

3

in which part of the forepart of the upper is broken away to show the manner in which the shank lining is turned back.

Figure 6 is a fragmentary view similar to Figure 5 showing the metatarsal and longitudinal arch cushions fastened to the underside of the shank lining.

Figure 7 is a plan view similar to Figure 5 but showing the shank lining returned and sealed in finished position.

This invention will be described with particular reference to a slip-lasting process. However, those skilled in the art will readily appreciate that the underlying principles of construction can be utilized with equal facility in a force-lasting process. A typical method of constructing shoes in accordance with this invention is begun by preparing and assembling the parts shown in Figure 1. These parts include an upper 10 which in the embodiment shown is adapted to form an open heel-open toe lady's shoe, a comparatively thin shank lining or flap 11 which is in part shaped to conform to the heel and shank portion of a sock lining 12 and a platform wrapper comprised of two parts 13 and 14 which are shown inverted in accordance with standard preliminary assembly technique. If a platform is not to be used, the platform wrapper may be omitted from this assembly.

Prior to the lasting operation, the aforementioned parts are assembled by placing the upper inside the upstanding portions of the platform wrapper so that the marginal lower edges 15 of the upper coincide with the lower edges 16 of the wrapper portions. The shank lining 11 is placed in overlapping face to face relationship with the sock lining in such a manner that the heel 17 and side edges 18 of the shank lining coincide with and are matched to the heel and side edges of the sock lining. The heel and side edges of the shank lining and the entire peripheral edge of the sock lining are turned over in the manner shown in Figure 3 and the matched portions placed inside the upper so that they lie alongside and coincide with the marginal edges of the upper and the platform wrapper.

It will be observed from an inspection of Figures 1 and 7 that the shank lining is notched as at 20 to receive the edge 21 of the heel strap of the upper. Forward of the heel strap notch is a gently curved lip 22 which is adapted to extend beyond the inner shank of the sock lining and overly the inner shank portion 23 of the upper thereby concealing the longitudinal arch button. This lip curves forward gently, returning substantially to the contour of the forward portion of the sock lining. In the embodiment shown, the shank lining does not have the same length as the sock lining, but is only sufficiently long so that when the respective heel portions of the sock lining and shank lining are placed together, the forward portion of the shank lining extends to approximately the center of the ball supporting portion of the sock lining. Thus, the shank lining need be only of sufficient length to cover and conceal the metatarsal button and provides a forward marginal sealing edge 24. The shank lining and sock lining are placed within the upper and platform wrapper and the side lip of the shank lining is turned up so that it resides against the inner side surface of the upper. The forward edge of the shank lining does not reach the forward edge of the sock lining and therefore lies flatly on the sock lining and without being turned under. Consequently, as shown in Figures 2 and 3, the heel and outer side edges 17 and 18

4

of the shank lining are turned over into flush relationship with the edges of the sock lining, platform wrapper and upper while the lip 22 of the shank lining is turned up against the upper and the forward edge of the shank lining is positioned directly on the sock lining. This assembly is then joined for the lasting operation by stitching the respectively adjacent parts to the periphery of the sock lining. The dotted lines 25 in Figure 1 indicate the stitch lines on the various parts. It will therefore be apparent that the shank lining, sock lining and platform wrapper are joined together at the heel. The upper, sock lining and platform wrapper are joined together at all points except at the heel, while the sock lining, upper, platform wrapper and shank lining are joined together along the outer side edge of the assembly.

By virtue of this construction, the flap or shank lining is firmly attached to the shoe and forms, in conjunction with the sock lining and the upper, an unsealed envelope which is adapted to later receive the metatarsal and longitudinal arch supporting buttons. Before placing the buttons in position and sealing the envelope, however, the shoe is lasted and as shown in Figure 4 the platform (not shown) and wedge-type heel (not shown) are attached to the sock lining. If desired, the seam may be recessed in a groove provided in the platform. The platform wrapper is then turned down from the seam and secured in position over the wedge-type heel and the platform in a conventional manner. The outsole and outer heel are also attached in place in accordance with well known techniques.

After the shoe is removed from the last, the envelope is opened by turning back the forward lip and the flap of the arch lining (see Figure 5). Appropriately shaped metatarsal 26 and longitudinal arch pads 27 formed from soft rubber or other suitable resilient material are then fastened in position on the underside of the flap as shown in Figure 6 or alternatively on the sock lining. Any convenient means can be used for securing in position but it has been discovered that adhesive is entirely satisfactory. The shank lining flap is then returned to its normal position shown in Figure 7 where it is secured in place against the sock lining and the upper by means of adhesive. Thus, the envelope is sealed and the pads securely fastened in position.

If, as preferred, the envelope is sealed by adhesive, it will be apparent that it can be easily unsealed to permit adjustment or replacement of the pads without destroying the shoe or necessitating rebuilding. Whenever adjustment or replacement of the pads is desired, it is only necessary to force the adhesive and turn the flap back whereupon the pads are exposed. The envelope may then be resealed with the pads in correct adjustment or with the replacement pads as the case may be.

The button envelope formed by the previously described process is firmly although impermanently secured in and is integral with the shoe structure. Particularly, attention is directed to the stitched seam between the sock lining and the shank lining at the heel of the shoe. Here the shank lining and sock lining are not only joined together but are firmly anchored to other heel parts. Hence, the shank lining is positively prevented from curling upward and away from the heel portion of the sock lining. Moreover, the shank lining is positively held against displacement under the repeated forward frictional forces exerted thereon by the foot.

While this invention has been disclosed in relation to a flap or shank lining which cooperates with the sock lining and inner shank portion of the upper to form an envelope which will accommodate both metatarsal and longitudinal arch supporting buttons, those skilled in the art will readily appreciate that the invention embraces the concept of providing a flap or shank lining which will form an envelope designed to accommodate only a metatarsal button or a longitudinal arch supporting button or some other type of button well known to those skilled in the art. For example, if it is only desired to build a longitudinal arch support button in the shoe, the flap need not extend beyond the shank of the upper but may terminate just forward of the button. Conversely, if it is only desired to include a metatarsal button in the shoe the sock lining need not be dimensioned so that it extends to the ball of the foot.

Having described my invention, I claim:

1. In a process for making slip-lasted shoes the steps of; assembling an upper, a sock lining and a flap adapted to overlie the sock lining in face to face relationship therewith, fastening said flap to said sock lining around the heel portions thereof to form an unsealed button-receiving envelope therewith and fastening said upper to said sock lining, slip-lasting the assembly thus formed whereby said flap conforms snugly to the last without substantially displacing said sock lining therefrom, fastening a heel and outsole to said lasted assembly, removing the shoe from the last, inserting at least one corrective button in said envelope and sealing said envelope.

2. The process of making a corrective shoe by

the slip lasted method, which process includes the steps of assembling an upper, a sock lining and a flap member adapted to be positioned on the surface of the sock lining in the completed shoe, said flap member being formed of thin sheet material and corresponding generally in contour to the heel and shank portions of the sock lining but having a portion extending laterally beyond the sock lining on the inner shank area thereof, securing together the edges of the upper, sock lining and flap with the sock lining and flap being secured only along the heel and the outer edge of the shank, said flap thereby defining an unsealed envelope, slip lasting the assembly, attaching a heel and outsole to the assembly while it is on the last, removing the assembly from the last, positioning and securing within the confines of the envelope a metatarsal pad and a longitudinal arch pad and finally sealing the envelope by securing the body of the flap to the sock lining and the laterally extending portion to the inner side surface of the upper.

CHARLES LONGINI.
